UNITED STATES PATENT OFFICE.

GEORGE BELL, OF CONCORD JUNCTION, MASSACHUSETTS.

YARN-CATCHER FOR SPINNING-MACHINES.

1,343,704.

Specification of Letters Patent. Patented June 15, 1920.

Application filed December 28, 1918. Serial No. 268,718.

To all whom it may concern:

Be it known that I, GEORGE BELL, a citizen of the United States, residing at Concord Junction, in the county of Middlesex and State of Massachusetts, have invented certain new and useful Improvements in Yarn-Catchers for Spinning-Machines, of which the following is a full, clear, concise, and exact description.

My present invention has for its principal object to provide means for holding the yarn in operative relation to the spindle, whereby the excessive waste of yarn which ordinarily takes place during the removal of full and the application of empty bobbins to the spindle is avoided.

Another object is to provide a device of this character which may be employed upon spinning mules of the type now in general use at a comparatively small cost, without the necessity of making extensive alterations in the construction of said mules.

With these and other objects in view, my invention consists of a support mounted, frictionally or otherwise, on the spindle, below the bobbin, at one side of which support is pivotally mounted an angular member, either arm of which is adapted to be moved into engagement with the spindle above or below the support, and being held in either of its two positions by a spring. A movable ring or collar having a reciprocating movement parallel to the axis of the spindle engages with one or the other of the arms of the angular member to move said arms into position to grasp or release the yarn to be wound on the bobbins.

In the accompanying drawings, in which like numerals of reference denote corresponding parts in all the figures;

Figure 1 is an elevational view of my invention applied to a spinning mule of ordinary form, a portion only of said mule being shown, in order that my invention may be more readily understood.

Fig. 2 is a plan view showing clearly the construction and operation of the catch operating ring, and

Fig. 3 is an enlarged plan view of the yarn catcher, the spindle being shown in section.

Referring to the drawings, 10 designates a portion of a rail in which are vertically mounted for rotation, the spindles 11. Only

two of these spindles are shown in Fig. 2, 55 but it is to be understood that the number of spindles employed is only limited by the capacity of the machine. These spindles are supplied with pulleys or whirls 12, by means of which they are rotated. A friction collar 13, for holding the bobbins 14, is mounted on the spindle 11 in any convenient manner.

Attached to the spindle 11 and rotatable therewith, is a sleeve 15. This sleeve 15 is located between the whirl 12 and the friction collar 13 and carries at its upper end a support 16, shown in plan in Fig. 3. This support 16 may be separate from the sleeve 15 and fastened thereto in any convenient manner, or it may be made integral with the sleeve 15, as by casting. An angular member, comprising two arms 17 and 18, connected to a central portion 19, is pivotally mounted at one end of the part 16. At the other end of the part 16 are two arms or projections 20 and 21, grooved on their ends to receive a coil spring 22, each end of which spring is attached to the ends of a pin 23 extending through and fastened to the part 19. The face of the arm 17 is grooved to fit the spindle 11, as clearly shown in Fig. 3, to more firmly grasp the yarn. The face of the arm 18 may be grooved also, but it is not essential.

In the position of the angular member shown in Fig. 1, the arm 17 is in engagement with the spindle, and gripping the yarn 24. In the other position of the angular member, the arm 18 will be in engagement with the sleeve 15. The position of the pin 23 with respect to the pivot point between the angular member and the support 16 is such that the angular member will stay in any position to which it has been moved; that is, in the position shown in Fig. 1, the arm 17 will be held in engagement with the spindle 11 by the spring 22 until forcibly moved away therefrom by the ring or plate 30.

Mounted on the rail 10 are bearing blocks 25 and 26, in which is rotatably mounted the shaft 27. These bearing blocks are attached to the rail 10 by bolts 28, or in any other suitable manner. Attached to the shaft 27 by set screws 29 is a plate 30 provided with perforations 31. On the end of the shaft 27 is fastened an operating lever

32 by means of which the outer end of the plate 30 is moved upward or downward with respect to the spindle 11, and being held in its extreme positions by the catch 33 engaging with one or the other of the notches 34 in a quadrant 35 fastened to the rail 10 by the bolts 36. The plate 30 in its movement engages one or the other of the arms 17 and 18, moving the same upward or downward 5 against the tension of the spring 22, until the pin 23 passes the pivot point of the angular member, when the spring 22 will force said arm into engagement with the spindle 11 or sleeve 15, respectively.

10 In the operation of the device, the arm 18 is usually in engagement with the sleeve 15, the plate 30 being in its lowermost position, as indicated by the dotted lines in Fig. 1. An empty bobbin 14 is placed on the spindle 11 and the operation of winding 15 the yarn 24 on the bobbin takes place in the usual manner, the faller wire 36 being moved upward and downward to guide the yarn onto the bobbin. When the bobbin 20 is full, the faller wire is depressed to guide the yarn 24 downward onto the spindle 11 and below the collar 13. After one or two turns of the yarn are on the spindle, the lever 32 is operated to move the arm 17 upward 25 into engagement with the spindle 11 to firmly hold the yarn 24. The full bobbin may now be doffed and an empty bobbin placed on the spindle. In the doffing the yarn breaks close to the spindle, but the 30 arm 17, holding the turns of yarn against the spindle, prevents the yarn from flying loose when the full bobbin is doffed. When the empty bobbin is in place, the faller wire 36 is again raised to guide the yarn 35 onto the bobbin. At any time before the bobbin is full, the plate 30 may be lowered to free the loose end of the yarn from the spindle, in preparation to repeat the operation above described.

40 It will be obvious, from the above description, that a substantial saving of yarn is effected over the methods now employed, and that but one or two turns of the yarn around the spindle are necessary for the doffing operation. These one or two turns amount at most to less than two inches. This seeming waste is all carried by the 45 next bobbin used, so that, in reality, no waste takes place. In the methods at present employed, not only is there a possible waste of two inches, but the dozen or fifteen turns of yarn around the spindle and which must be cut from the spindle by a knife or other like implement, is an absolute waste, and this waste is avoided by the 50 use of my invention.

55 While I have described the preferred embodiment of my invention, it will be understood that minor changes in the details of construction and arrangement of parts may

be made within the scope of the appended claims without departing from the spirit of the invention.

Having thus described my invention, what I claim and desire to secure by Letters Pat- 7 ent, is:—

1. A yarn catcher for spinning machines, comprising, a spindle, a support mounted thereon and rotatable therewith, a holding member pivotally mounted on said support, 7 and adapted to hold the yarn extending from the mule to the bobbin, against the spindle.

2. A yarn catcher for spinning machines comprising, a spindle, a support mounted 8 thereon and rotatable therewith, a holding member pivotally mounted on said support and including a pair of radially extending arms, means for selectively engaging said arms to rock the holding member into or 8 out of position to hold the yarn extending from the mule to the bobbin, against the spindle.

3. A yarn catcher for spinning machines comprising, a spindle, a support mounted 91 thereon and rotatable therewith, a holding member pivotally mounted on said support and including a pair of radially extending arms, means for selectively engaging said arms to rock the holding member into or 91 out of position to hold the yarn extending from the mule to the bobbin, against the spindle, and means for retaining the holding member in either its operative or non- 10 operative position.

4. A yarn catcher for spinning machines comprising, a spindle, a support mounted thereon and rotatable therewith, a holding member pivotally mounted on said support, and including a pair of radially extending 10 arms, a pivotally mounted plate having a perforation encircling the spindle and adapted to selectively engage said arms to rock the holding member on its pivot into or out of position to hold the yarn extending 11 from the mule to the bobbin, against the spindle.

5. A yarn catcher for spinning machines comprising, a spindle, a support mounted thereon and rotatable therewith, a holding member pivotally mounted on said support, and including a pair of radially extending arms, a pivotally mounted plate having a perforation encircling the spindle and adapted to selectively engage said arms to 11 rock the holding member on its pivot into or out of position to hold the yarn extending from the mule to the bobbin, against the spindle, and a spring for retaining the holding member in either its operative or non- 120 operative position.

6. A yarn catcher for spinning machines comprising, a spindle, a support mounted thereon and rotatable therewith, a holding member pivotally mounted on said support, 130

and including a pair of radially extending arms, a spring extending from said support to said holding member and adapted to retain the holding member in its operative or 5 non-operative position, a pivotally mounted plate having a perforation encircling the spindle and adapted to selectively engage said arms to rock the holding member on its pivot, a lever for operating said pivoted plate, and means for locking the lever to hold the pivoted plate in either of its positions.

7. In a spinning machine, in combination, a rail, a spindle rotatably mounted thereon, 5 means for rotating the spindle, a bobbin

holder on said spindle, a yarn holding device pivotally mounted on said spindle below the bobbin holder, a faller wire and means for moving the same downwardly when the bobbin is full to guide the yarn 20 onto the spindle below the bobbin holder, operating means for moving the yarn holding device into position to hold the yarn against the spindle while the full bobbin is 25 being doffed.

In witness whereof, I hereunto subscribe my name this 21st day of December, A. D. 1918.

GEORGE BELL.
